UNITED STATES PATENT OFFICE.

FRANK LEMONT DODGSON, OF TROY, NEW YORK, ASSIGNOR, BY MESNE ASSIGNMENTS, TO GENERAL RAILWAY SIGNAL COMPANY, OF GATES, NEW YORK, A CORPORATION OF NEW YORK.

APPARATUS FOR CONTROLLING MOBILE PARTS OF RAILWAY SUPERSTRUCTURES.

SPECIFICATION forming part of Letters Patent No. 774,313, dated November 8, 1904.

Application filed January 17, 1901. Serial No. 43,620. (No model.)

To all whom it may concern:

Be it known that I, FRANK LEMONT DODGSON, a citizen of the United States, and a resident of Troy, in the county of Rensselaer and 5 State of New York, have invented certain new and useful Improvements in Apparatus for Controlling Mobile Parts of Railway Superstructures, of which the following is a specification.

10 This invention relates to improved apparatus for controlling railway traffic-controlling devices, and particularly by controlling the operating-lever thereof while a car is upon the particular portion of the track to which 15 the part relates.

The object of the invention is to control the operation of a mobile part of a railway traffic-controlling device, but at the same time to render it possible to actuate the mobile part 20 if the track devices fail to work.

The invention consists in the apparatus hereinafter described and claimed.

The invention is described and shown herein as applied to a railway-signal that is set 25 automatically to "danger" by the train and by making the train actuate the operating-bar so as to set the signal to "danger." The position of the operating-bar thus is an indicator to the operator. Besides its use in connection with signals, this invention is capable 30 of application to switches and to other movable parts of railway traffic-controlling devices, such as crossing-gates, &c.

Mechanical slots are well known. They 35 consist of means (usually on the signal-pole) for breaking the mechanical connection between the operating-lever and the signal. This connection is made by energizing an electromagnet which when deenergized disconnects the signal from the operating-lever 40 and allows the signal to return to "danger" by gravity. If the electrical apparatus does not work, or if, in other words, the connecting-magnet is not energized, the leverman loses 45 control of the signal. In electrical signaling the same result is accomplished by breaking the circuit between the lever and the signal, (usually at the signal,) so that the signal re-

turns to "danger" by gravity, while the lever may remain reversed. In these cases the 50 leverman loses control of the signal, and it is obvious that under these circumstances the lever may be in one position while the signal is in another and that the position of the lever does not necessarily show the position of 55 the signal. In the cases above specified dependence is put upon the uncertain action of gravity to return the signal to "danger."

In the present apparatus gravity is not employed for returning the signal to "danger," 60 and the position of the operating-lever always shows the position of the signal, and, further, if the electrical connections in the device should at any time fail the leverman nevertheless retains full control of the signal. In 65 the embodiment of this invention herein described it is combined with a fluid-pressure or pneumatic apparatus for setting the signal to "safety" and for returning it to "danger," 70 which apparatus comprises also a return indication produced by fluid-pressure or pneumatically to the operating-station, involving also a connection with and an operation of the operating-lever. This embodiment of 75 the invention also comprises an electric circuit guarding a particular section of the railway-track that produces through suitable mechanism an automatic movement of the operating bar or lever and also resists through suitable mechanism the movement of said bar 80 or lever, and thus controls movement of said bar. It will be seen that other ways of controlling movement of said bar may be accomplished by this invention. Electric and mechanical appliances may be employed in place 85 of the pneumatic devices herein described.

In the drawings, Figure 1 is a diagrammatic view of the apparatus embodying the invention just described. Figs. 2 and 3 are respectively side and front elevations of one of 90 the valves and its electrical operating mechanism. Fig. 4 is a vertical section of said valve on the line 4-4 of Fig. 2; and Fig. 5 is a top plan view of a pair of relay-valves shown at the foot of the mast in Fig. 1, portions being removed to show the construction. Fig.

6 is an elevation of the same pair of valves, the right-hand valve being shown in vertical section. Figs. 7, 8, and 9 are cross-sections on the lines 7 7, 8 8, and 9 9 of Fig. 6. Fig. 5 10 is a vertical section through the indicator-valve on the signal-mast; and Figs. 11 and 12 show, respectively, the faces of the seat and of the slide of an operating-valve at the tower.

The signal-mast A bears the usual counter-balanced signal-blade A', that is moved to the safety and danger positions by a cylinder A², having a piston a' and a connecting-rod a² attached to the signal-blade. The piston is operated by pneumatic pressure derived from 10 the reservoir X through a supply-pipe X', that is led through two relay-valves R² R³ by a branch x¹⁰. From the valve R³ a pipe f' leads to one end of the cylinder, and from the other relay-valve, R², a pipe e leads to the other 15 end of the cylinder through a branch e' and also to an indicator-valve B. Upon the signal-mast is pivoted a lever A³ in such a position that a nut or striker a³ upon the piston-rod or on the connecting-rod a² or upon some 20 part moving with the semaphore-blade strikes the lever when the signal-blade A' is in the danger position and tilts the lever so far as to operate the valve-stem b³ of the indicator-valve B. The indicator-valve B, through the 25 pipe n, leads to a relay-valve R', connected with a cylinder I¹⁰, containing a piston i', carrying upon its piston-rod a roller i¹⁰, moving in a slot in the operating lever or bar L, to be hereinafter described.

30 The operating-bar is connected by a link with a valve V', that controls connections between the supply-pipe X' and the pipes p and o, that operate the relay-valves R² and R³ at the signal. The supply-pipe X' is always in 35 connection with the valve V' and with the relay-valves R² and R³, and according as one of the relay-valves or the other is opened air-pressure is introduced to one end or the other of the cylinder A², whereby the signal is 40 moved to "danger" or to "safety." The shifting of the valve V' operates the relay-valves R² and R³ so as to permit the passage of air from the supply-pipes just described to the cylinder. When the piston in the cylinder 45 A² is raised, the signal is set to "safety" and the valve B is released from the action of the lever A³, whereupon the air-pressure is exhausted through the valve B from the indicating-pipe n, which actuates the relay-valve 50 R', which opens the relay-valve R' to the exhaust and cuts off air-pressure from the supply-pipe X' through said relay-valve into the cylinder I¹⁰, thus relieving its piston from pressure and releasing the lever L for further 55 operation and also indicating the fact that the signal has been set to "safety."

The continued pressure in the lower end of the cylinder A² retains the signal in the safety position.

60 65 On reversing the movement of the lever L

the valve V' is carried back, connecting the pipe p with the supply-pipe X' and connecting the pipe o with the atmosphere, thus permitting the relay-valve R³ to exhaust and cutting off the passage of air-pressure through said 70 relay-valve. Pressure in the pipe p opens the relay-valve R² and permits air-pressure to pass into the pipe e and through the branch e' into the upper end of the cylinder A², depressing the piston and setting the signal back 75 to "danger." As soon as the signal has returned to "danger" the lever A³ is tilted and the valve B is shifted so as to connect the pipe n with the pipe e. This carries a pressure to the relay-valve R', connects the supply-pipe X' with the cylinder I¹⁰ through the relay-valve R', and raises the piston thereof. The pressure introduced through the pipe n not only releases the lever for further 80 operation, but also indicates the fact that the signal has gone back to "danger." From the position of the lever just described it may be set back to its original position, in which the supply-pipe X' is cut off and the pipes o and p are open to the atmosphere. This closes 85 the relay-valve R'.

As thus far described the apparatus is the same as that shown and described in United States Letters Patent No. 647,483, granted April 17, 1900, for railway switch and semaphore apparatus. The form of slot with which the roller i¹⁰ engages is not the same, however, in the present device as in that of 90 said patent. In the patent the form of said slot is such as to produce an automatic movement of the lever L at the end of its stroke. In the present device the slot just mentioned does not have this function, although the invention herein set forth may be used in connection with the apparatus set forth in said 95 patent.

Each relay-valve R' R² R³ is of the same construction, and consists of a chamber r², divided into two parts by a flexible diaphragm r²⁰, and an operating-pipe o p n connects with the lower part of said chamber, so that pressure or reduction of pressure in the pipe may 100 actuate the diaphragm r²⁰. A free passage r²² leads from the upper portion of the diaphragm-chamber over the diaphragm r²⁰ to 105 the outer air, so that the diaphragm may rise and fall freely. The valve-stem r²⁷ rests upon the diaphragm r²⁰, so that the stem and its valves may rise and fall with the movement 110 of the diaphragm. A cylindrical bore in the casing of the valve has two pistons r²² and r²³, which are carried by the valve-stem. The upper piston r²³ when in its lowest position rests upon a valve-seat r²³⁰, and the lower piston when in its highest position against a 115 valve-seat r²²⁰. One or more exhaust-pipes r²² connect with the chamber of the valve in such a manner that when the piston r²² is in its lowest position the bore is open to 120 the exhaust, and when said piston is in its 125 highest position the bore is closed. One or more exhaust-pipes r²² connect with the chamber of the valve in such a manner that when the piston r²² is in its lowest position the bore is open to 130 the exhaust, and when said piston is in its

highest position the exhaust-passages r^{102} are closed.

A spring r^{30} , inside the valve-casing, tends to depress the pistons r^{22} r^{23} . An inlet-passage 5 r^{10} connects the supply x^{10} with the upper part of the valve-casing on the upper side of the piston r^{23} , so that air-supply in the pipe X' passes into the casing of the valve through the channel x^{10} and upward through the passage r^{10} to a chamber r^{232} in the upper end of the valve-casing.

A port r^{231} connects the chamber r^{232} with the interior of that portion of the bore in which the piston r^{23} moves, so that when said 15 piston is in its lowest position this bore is closed; but when the piston is in its highest position the port is open and connects the supply-pipe X' with the interior of the bore in which the two pistons move. An outlet-passage e^{11} is connected with the outlet-pipe e, f , or r^{100} and with the bore between the pistons, so that pressure that lifts the diaphragm connects the inlet r^{10} with the outlet e^{11} ; but when 20 the diaphragm is not raised the piston r^{23} closes the inlet r^{10} and the piston r^{22} uncovers the exhaust and connects the outlet e^{11} with the exhaust.

The indicator-valve B contains a pair of pistons $b' b^2$, connected by a stem b^3 , which extends 30 downward and outside of the valve-casing in order to be acted upon by the lever A^3 . The pistons work in a cylindrical bore in the casing, which has a seat b^{10} , against which the piston b' rests when in its lowest position, and a second seat b^{20} , against which the piston b^2 rests when in its highest position. A pipe n connects by a port in the valve-casing with the space around the stem b^3 . A pipe e is connected to a suitable portion of the casing by 35 a channel e' and through a port e^{10} connects with the cylindrical bore in which the piston b' slides and so that when the piston b' is in its lowest position it closes the port e^{10} , but when the piston is in its highest position the 40 port is open. When the pistons are raised, the pipe e is connected with the pipe n , and when the pistons are lowered the connection from the pipe e is cut off and the pipe n is connected with an exhaust-passage b^{21} .

50 The valve V' has a valve-seat V^{100} , in which are four rectangularly-arranged ports v^{101} , v^{102} , v^{103} , and v^{104} and a long lengthwise exhaust-port v^{100} , set between the ports v^{101} and v^{105} on one side and v^{102} and v^{104} on the other side. The ports v^{101} and v^{103} connect, respectively, with the pipes o and p , and the ports v^{102} and v^{104} connect by a Y-shaped passage v^{105} with the supply-pipe X' . The slide V^{200} has a long middle exhaust-port v^{200} , that registers at all times with the port v^{100} , and three other ports, v^{201} , v^{203} , and v^{205} , in line with each other on one side of the port v^{200} , and a single port v^{202} on the other side of the port v^{200} . The ports v^{202} and v^{205} are connected by a passage 55 in the body of the slide, and passages in the

body of the slide connect the ports v^{201} and v^{203} with the exhaust-port v^{200} . The ports v^{202} and v^{205} have each a face area equal to that of one of the ports v^{101} , v^{102} , v^{103} , and v^{104} in the valve-seat and are adapted to connect either pair of the ports v^{101} and v^{102} or v^{103} with v^{104} . The ports v^{201} and v^{203} are each long enough to connect both the ports v^{103} and v^{101} with the exhaust v^{100} at the same time, and they and the port v^{205} are so set in the slide-face that when 70 the port v^{205} registers with either port v^{101} or v^{103} the other port v^{103} or v^{101} registers with the port v^{201} or with the port v^{203} . Hence when the slide is at either limit of its motion the supply X' is cut off and both of the pipes o 80 and p are open to the exhaust, and the slide may be so set at two intermediate positions that the supply X' is connected with the pipe o while the pipe p is exhausted or the supply X' is connected with the pipe p while the pipe o is exhausted.

In addition to the slot i^{10} for the bar H of the interlocking board and the slot in which the roller i^{70} runs the lever L has another slot having a portion m in a line corresponding to 90 the line of movement of the bar L and a second portion m' , extending diagonally downward and across the bar from the portion m . In this slot runs a pin or roller m^{10} , borne by a piston m^0 in the cylinder M . This cylinder 95 is connected by a pipe q , through a valve Q , with the supply-pipe X' by means of a branch x^{100} , that may be conveniently led also to the relay-valve R' .

The valve Q is shown in vertical section in 100 Fig. 4. It has a central chamber q' connecting by the passage q^{10} with the pipe q , leading to the cylinder M , and a chamber q^2 above the chamber q' and connecting by the passage q^{20} with the inlet-pipe x^{100} . The valve also has an 105 exhaust-passage q^3 . Both the upper chamber q^2 and the exhaust-passage are connected with the central chamber q' . A valve-stem q^4 passes upward through the central chamber q' and bears valves $q^5 q^6$, which are pressed downward by a spring q^7 . The valves $q^5 q^6$ are set at such a distance apart that they may upon receiving proper movement cut off the passage connecting the central chamber q' with the exhaust q^3 and at the same time open connection 110 between the inlet x^{100} and the closed upper chamber q^2 , as shown in Fig. 4, or when the rod q^4 is depressed by the spring q^7 the passage between the central chamber q' and the upper chamber q^2 is closed, cutting off the cylinder M from the supply x^{100} , and the passage between said central chamber and the exhaust q^3 is opened. Consequently when the valve-rod q^4 is raised pressure from the inlet x^{100} is conducted through the valve, and when 120 the valve-rod is lowered the pressure is cut off and the cylinder is connected to the exhaust. It is obvious that when the roller m^{10} is in the horizontal portion m of its slot the piston 125 cannot move up or down, provided the bar L 130

is firmly held in suitable guides, but that after the bar L has been moved in the direction of the arrow in Fig. 1 far enough to carry the roller into the beginning of the diagonal portion m' of its slot the further motion of the bar will depress the piston. This depression, however, can occur only if the pipe q is connected to the exhaust. If the roller m^{10} is in the lower end of the diagonal portion m' of its slot air-pressure introduced from the supply-pipe X' through the valve Q will raise the piston and will produce a movement of the bar L in a direction opposite to that of the arrow until the roller strikes the upper end of the slot m' opposite the beginning of the horizontal portion m of the slot, whereupon the movement of the piston will cease and the setting of the bar, so that the roller is held between the two sides of the portion m' of the slot, must be produced by a further movement of the lever by hand. At this position of the roller m^{10} in its slot the roller i^{10} is against the shoulder l^2 and pressure must be admitted to the cylinder I^{10} to lift the roller from said shoulder before the lever can be returned to its original position. This admission of pressure to the cylinder I^{10} can occur only after the signal has returned to the danger position, as explained above.

The valve-rod q^4 is operated by the armature t of the electromagnet T. The electromagnet T is connected by suitable conductors t', t^2 with the armature s' of the relay-magnet S and with a battery T^0 . The relay-magnet S is connected by suitable conductors S', S^2 with the two rails Z Z' of a section of track that is insulated, as by the insulators z. A battery W or other suitable source of electricity is connected by suitable wires w, w' with the two rails Z Z' of said insulated track-section. The circuit of the electromagnet T passes through the armature s' of the relay and through a suitable contact-point s^0 , so arranged that when the magnet S is deenergized the circuit through the electromagnet T is completed and the magnet T is energized, thus moving the armature t , raising the valve-rod q^4 , and admitting air to the cylinder M. The magnet S is deenergized only when the battery-circuit of the battery W is shunted by the presence of an axle and its pair of wheels U (shown in dotted lines) upon the insulated rails Z Z', for at other times the current from the battery W passes through the wire w' , the rail Z, the wire S', the magnet S, the wire S ^{2} , the rail Z', and the wire w .

If a car or a single pair of wheels, with their axle, is upon the insulated track-section, the magnet S is deenergized, the magnet T is energized, the valve-stem q^4 is lifted, permitting air-pressure to pass through the valve Q, and thus the elevation of the piston maintains the roller m^{10} in the upper end of its slot, and the lever is practically locked or held against movement; but when the magnet S is again

energized by the removal of the car or of a pair of wheels and axle from the insulated track-section the magnet S is energized, the current is broken between its armature and the contact-point s^0 , the magnet T is deenergized, the valve-rod q^4 falls, pressure is cut off from the cylinder M, and the pipe q is connected to the exhaust q^3 , thus permitting again free movement of the lever L.

It is of course clear that if these electrical devices are cut out as soon as the pipe q is normally connected with the exhaust q^3 the lever L can be moved freely backward and forward, because the piston in its upward and downward movement will merely draw in and force out the air through the exhaust q^3 of the valve Q. Consequently if the battery T^0 or W should fail or any of the electrical contacts or conductors should break the lever is still freely movable and the leverman still has control over the signal through the pneumatic apparatus described.

The slot in the lever L, in which the roller i^{10} moves, is provided with an upper horizontal portion l and a lower horizontal portion l' and an intermediate connecting-space having a shoulder l^2 in line with the lower horizontal slot l' . Opposite the end of the upper horizontal slot l is a downwardly-inclined surface l^3 . When, therefore, the lever L is pulled in the direction of the arrow, the incline l^3 meets the roller i^{10} and forces it downward and into the slot l' , in which it is held, so that pressure in the cylinder cannot produce movement of the piston. When there is no pressure in the cylinder and the roller i^{10} is in the slot l' , the lever L may be moved in a direction contrary to that of the arrow until the shoulder l^2 strikes the roller, whereupon movement of the lever is stopped until an air-pressure in the cylinder I^{10} lifts the piston so far as to bring the roller i^{10} opposite the upper slot l , whereupon further movement of the lever L by hand carries the roller into said slot l , whereby the piston is held stationary until the lever is moved by hand in the direction of the arrow.

In order to follow the operations of this device through, let us assume that the parts are in a normal position, (shown in Fig. 1,) the signal being at "danger," the reservoir X being connected with the valve V', the valve Q, and the relay-valves R', R ^{2} , and R ^{3} , but the air-pressure from the supply X' is cut off from all said valves. The pipes o and p are exhausted. A train approaches and is to enter upon the insulated track-section. The operator pulls the lever L outward in the direction of the arrow, which depresses the interlocking bar H, releases the roller i^{10} from the locking-slot l , carries it downward and into the locking-slot l' , releases the roller m^{10} from the locking-slot m and carries it to the lower end of the slot m' , shifts the valve V' so that the supply-pipe X' is connected through the

pipe o , (at the same time connecting the pipe p with the atmosphere,) and pressure is put upon the relay-valve R^3 , lifting said valve and introducing air-pressure into the lower end of the cylinder A^2 , raising its piston and depressing the semaphore-blade to the safety position.

The signal is held at "safety" by the continuance of pressure in the pipe f through the open relay-valve R^3 . The train now enters the insulated track-section, the circuit of the relay-magnet S is shunted, and said magnet is de-energized, thus energizing the magnet T , opening the valve Q , and introducing air-pressure into the cylinder M . This lifts the roller m^{10} , which moves along the slot m' and shifts the lever L until the roller i^{10} strikes the stop face or shoulder l^2 . This movement of the lever L shifts the valve V' so as to connect the pipe o with the atmosphere and to exhaust the relay-valve R^3 and to connect the pipe p with the supply X' . This opens the relay-valve R^2 and introduces pressure into the pipe e and by the branch e^2 into the upper end of the cylinder A^2 and resets the signal to "danger." The lever A^3 now actuates the valve B , and this carries air-pressure to the relay-valve R' , which opens and admits air to the cylinder I^{10} , lifting its piston and raising the roller i^{10} away from the shoulder l^2 and up to a position opposite the slot l . It will be seen that the entry of a car upon the insulated track-section has set the signal automatically to the danger position. This position of the parts is maintained while the car is on the insulated track-section. The position of the lever shows that the signal is at "danger" and that the lever motion must be completed in a direction contrary to the arrow in Fig. 1 before a new operation of the signal. There is pressure in the cylinders M and I^{10} , and pressure in the former cylinder will resist any operation of the lever L in the direction of the arrow to set the signal to "safety."

As soon as the car has moved off the insulated section the magnet S is again energized, the magnet T is de-energized, the armature t falls, and the valve Q is set so as to cut off the air-pressure from the supply X' and to open the cylinder to the exhaust through the pipe q . This relieves the pressure of the roller m^{10} in its slot, and the signal is free to be operated by hand. It remains, however, at the danger position. The leverman now moves the lever L and the valve V' back to the position shown in Fig. 1, which sets the rollers m^{10} and i^{10} in their locking-slots m and l and connects the pipes o and p with the atmosphere. The relay-valve R^2 is thus relieved from pressure and connects the pipes e e^2 and the cylinder to the atmosphere. The valve B is closed, as above described, as soon as the signal-blade has been set to "danger." The tappet H is returned to place with the lever L .

It will be noted that the return of the operating-bar is of course followed by the return of the signal-blade or movable part from the abnormal or safety position to the normal or danger position thereof and that the resistance of the roller m^{10} in the slot m' when pressure exists in the cylinder M opposes movement of the operating-bar in a direction contrary to that of the automatic return or from the normal or danger position to the abnormal or safety position of the signal or movable part and that this resistance to movement is effective when the roller m^{10} is in the horizontal slot m and an attempt is made to pull the operating-bar in the direction of the arrow in Fig. 1 while pressure exists in the cylinder M .

By this invention the operating-bar of a railway superstructure device may be controlled, moved, or held—for example, by fluid-pressure mechanism—through track-circuit mechanism. By it also a signal may be set to "danger" automatically by the entry of a pair of wheels on the insulated track-section. By it also the operator is notified by the position of the lever that the signal is at "danger," and by it also the operator is notified by resistance to his effort that he must not set the signal to "safety" until the train or pair of wheels has left the track-section, whereupon automatically the said resistance is removed. It is obvious that this invention is applicable to track-sections relating to signals, switches, &c., at any distance from the operating-station to which their operating mechanisms may reach.

In the following claims the means for producing or resisting motion of the operating-bar may be applied to the bar itself or to a part that is connected to or moves with said bar.

What I claim is—

1. In an apparatus for controlling a movable part of railway traffic-controlling devices, a movable part having a normal position, operating power mechanism therefor comprised of a manually-operated operating-bar—a track-circuit, and automatically-operated means controlled by the track-circuit for producing an automatic return movement of said bar and of said movable part toward the normal position of the latter after a movement of said operating-bar to a position whereby said movable part is operated, substantially as described.

2. In an apparatus for controlling a movable part of railway traffic-controlling devices, a movable part having a normal position, operating mechanism therefor comprising a manually-operated operating-bar, a track-circuit, and automatically-operated means controlled by the track-circuit for producing an automatic return movement of said bar and of said movable part toward the normal position of the latter after a movement of said operating-bar to a position whereby said movable part is operated and for resisting movement of the bar

in a direction contrary to the returning movement thereof after the last-mentioned movement has occurred, substantially as described.

3. In an apparatus for controlling a movable part of railway traffic-controlling devices, a movable part having a normal position, operating mechanism therefor comprising a manually-operated operating-bar, a fluid-pressure device engaging the bar and adapted to produce automatic movement thereof from the abnormal toward the normal position thereof and to control the movement thereof from the normal to the abnormal position, valve mechanism for controlling the inlet to and exhaust from said fluid-pressure device, a track-circuit, and automatically-operated mechanism controlled by the track-circuit for controlling said valve mechanism, whereby automatic return movement of said bar and of said movable part toward the normal position of the latter is effected after a movement of said operating-bar to a position whereby said movable part is operated, substantially as described.
4. In an apparatus for controlling a movable part of railway traffic-controlling devices, a movable part having a normal position, operating mechanism therefor comprising a manually-operated operating-bar, a fluid-pressure device engaging the bar and adapted to produce automatic movement thereof from the abnormal toward the normal position thereof, and to control the movement thereof from the normal to the abnormal position, valve mechanism for controlling the inlet to and exhaust from said fluid-pressure device, a track-circuit and automatically-operated mechanism controlled by the track-circuit for controlling said valve mechanism, whereby said fluid-pressure device produces automatic return movement of said bar and of said movable part toward the normal position of the latter after a movement of said operating-bar to a position whereby said movable part is operated and resists movement of said bar from the normal to the abnormal position after movement of the movable part to the normal position has occurred, substantially as described.
5. In an apparatus for controlling a movable part of a railway apparatus of the kind specified, a movable part, fluid-pressure mechanism for setting said movable part to two different positions, a manually-operated operating-bar for bringing said fluid-pressure mechanism into action, two fluid-pressure devices for controlling the movement of said bar, one of said fluid-pressure devices being actuated in correspondence with the desired positions of said movable part, a track-circuit, and mechanism controlled by the track-circuit for controlling the movement of the other of said fluid-pressure devices, substantially as described.

6. In a railway signal apparatus, a signal-blade having a normal danger position, operating mechanism therefor comprising a manu-

ally-operated operating-bar, a track-circuit, and automatically-operated means controlled by the track-circuit for producing automatic return movement of said bar and of said signal-blade to the danger position of the latter after a movement of said bar to a position whereby the signal-blade is set to safety, substantially as described.

7. In a railway signal apparatus, a signal-blade having a normal danger position and a safety position, fluid-pressure operating mechanism therefor, a manually-operated operating-bar for controlling said fluid-pressure mechanism, a track-circuit, and automatically-operated means controlled by the track-circuit for producing automatic return movement of said bar and of said signal-blade to the danger position of said blade after a movement of said bar to a position whereby the signal-blade is set to safety, substantially as described.

8. In a railway signal apparatus, a signal-blade having a normal danger position and a safety position, operating mechanism therefor comprising a manually-operated operating-bar, a track-circuit, and automatically-operated means controlled by the track-circuit for producing automatic return movement of said bar and of said signal-blade from the safety to the danger position of the blade and for resisting movement of said bar toward the safety position after said automatic movement has occurred after a movement of said bar to a position whereby the signal-blade is set to safety, substantially as described.

9. In a railway signal apparatus, a signal-blade having a normal danger position and a safety position, operating mechanism therefor comprising a manually-operated operating-bar, a fluid-pressure device engaging said bar and adapted to control the movement thereof, valve mechanism for controlling the inlet to and exhaust from said fluid-pressure device, a track-circuit, and automatically-operated mechanism controlled by the track-circuit for actuating said valve to produce a movement of said bar and signal-blade from the safety toward the danger position thereof after a movement of said bar to a position whereby the signal-blade is set to safety, substantially as described.

10. In a railway signal apparatus, a signal-blade having a normal danger position and a safety position, operating mechanism therefor comprising a manually-operated operating-bar, a fluid-pressure device engaging said bar and adapted to control the movement thereof, valve mechanism for controlling the inlet to and exhaust from said fluid-pressure device, a track-circuit, automatically-operated mechanism controlled by the track-circuit for actuating said valve to produce a movement of said bar and signal-blade from the safety toward the danger position thereof after a movement of said bar to a position whereby the

signal-blade is set to safety, and for resisting movement of said bar in a direction opposite to said automatic movement thereof, after said automatic movement has occurred, substantially as described.

11. In a railway signal apparatus, a signal-blade, fluid-pressure mechanism for setting said signal-blade into the safety position, a manually-operated operating-bar for bringing said fluid-pressure mechanism into action, two fluid-pressure devices for controlling the movement of said bar, one of said fluid-pressure devices being actuated in correspondence with the signaling positions of said signal, a track-circuit, and mechanism controlled by the track-circuit for controlling the movement of the other of said fluid-pressure devices, substantially as described.

12. In a railway signal apparatus, a signal-blade, operating mechanism for actuating said

signal-blade, a manually-operated operating-bar for bringing said operating mechanism into action, a device for controlling the movement of the said bar controlled by the position of the signal-blade, a fluid-pressure device engaging said bar and adapted to produce movement thereof, a valve for controlling the inlet to and exhaust from said fluid-pressure device, an insulated track-section, an electrical circuit through said section and comprising a relay-magnet, an electrical circuit opened and closed by said relay-magnet, and an electromagnet in said last-mentioned circuit for operating said valve, substantially as described. 25 30
